CLAIM

We claim the ornamental design for a rear bumper, as shown and described.

DESCRIPTION

FIG. 1 is a left, top, and rear perspective view of a rear bumper,

FIG. 2 is a bottom plan view thereof,

FIG. 3 is a rear elevation view thereof,

FIG. 4 is a right, bottom, and rear perspective view thereof,

FIG. 5 is a right side elevation view thereof,

FIG. 6 is a right, top, and front perspective view thereof,

FIG. 7 is a left side elevation view thereof,

FIG. 8 is a top and rear perspective view thereof,

FIG. 9 is a top and rear-perspective view thereof; and,

FIG. 10 is a top plan view thereof.

All broken lines illustrate portions of the rear bumper to which the design is applied that form no part of the claimed design. Specifically, the dot-dash broken lines depict the limits of the claim and form no part of the claimed design.
